CLAIM

The ornamental design for a cosmetic bag, as shown and described.

DESCRIPTION

FIG. 1 is a front, top and left side perspective view of a cosmetic bag, showing my new design;

FIG. 2 is a rear, bottom and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the cosmetic bag shown in an alternate state of use;

FIG. 10 is a perspective view of the cosmetic bag shown in a closed state of use;

FIG. 11 is a perspective view of the cosmetic bag shown with the mirror removed for ease of disclosure; and,

FIG. 12 is a rear perspective view thereof.

The broken lines shown in the drawings illustrate portions of the cosmetic bag that form no part of the claimed design.
